UNITED STATES PATENT OFFICE.

HENRY B. COOLEY, OF NEW BRITAIN, CONNECTICUT, ASSIGNOR TO THE AMERICAN PAPER GOODS COMPANY, OF KENSINGTON, CONNECTICUT, A CORPORATION OF NEW JERSEY.

TYPE-CHASE AND FORM-CYLINDER FOR PRINTING-PRESSES.

1,008,016.

Specification of Letters Patent.

Patented Nov. 7, 1911.

Application filed January 25, 1910, Serial No. 539,940. Renewed March 31, 1911. Serial No. 618,132.

To all whom it may concern:

Be it known that I, HENRY B. COOLEY, a citizen of the United States, and resident of New Britain, in the county of Hartford and State of Connecticut, have invented a new and useful Type-Chase and Form-Cylinder for Printing-Presses, of which the following is a specification.

My invention relates to a type chase and form cylinder for printing presses with the object in view of providing a substantial support for the chase both edgewise and at the back so that the type or furniture may be securely locked in the chase without danger of springing the chase and for the ready removal and replacement of the chase and for holding it securely in position.

The type of cylinder which I have chosen to illustrate my invention is a rotary flat bed cylinder and is shown as having two oppositely disposed flat beds separated by cylindrical segments.

In the accompanying drawings, Figure 1 is a view of the form cylinder in elevation showing the type chases in edge elevation, Fig. 2 is a view taken in a plane at right angles to that of Fig. 1, showing a partial plan view of one of the type chases, Fig. 3 is a transverse section in the plane of the line A—A of Fig. 1, showing the chase retaining slides closed, Fig. 4 is a partial section in the same plane showing a chase retaining slide open, Fig. 5 is a view of the same in elevation, and Fig. 6 is a plan view of the same.

The form cylinder is denoted as a whole by 1. It is provided with two oppositely disposed flat beds 2 and 3, separated at the periphery of the cylinder by cylindrical segments 4 and 5. The type chases to be received on the beds 2 and 3 are denoted by 6 and 7, respectively. They are quite similar in structure and a description of one will suffice for both. Referring to the chase 6, its end edges are beveled, as shown at 8 and 9, to fit and slide in undercut grooves 10 and 11 in the rims at the opposite ends of the cylinder. The rear and front edges of the chase are also beveled, as shown at 12 and 13, to fit the inwardly directed slanting faces of the keepers at rear and front. The rear edge 12 of the chase is recessed at its

opposite ends, these recesses being denoted by 14, 15, to permit the sliding keepers to be slid into and out of locking position.

55

The fixed keepers for receiving the front edge 13 of the chase consists of thin plates 16, 17. These fixed keepers are curved to conform to the curve of the cylindrical segment and project beyond the face of the bed 60 2 a distance preferably about the thickness of the chase. They are each secured in place by two screws 19, 20. The sliding keepers, two for each chase, are located in position to slide into and out of the recesses 65 14, 15, at the rear edge of the chase. The sliding keepers for the chase 6, are denoted by 21, 22. They are each provided with one or more, in the present instance with one, elongated shouldered slot 23 through 70 which a set screw 24 extends, the under face of the head of the screw engaging the shoulder within the slot. The sliding movement of the sliding keepers is sufficient to permit the end of the keeper to overlap the beveled 75 edge of the chase to an extent preferably equal to the thickness of the chase. Both the fixed and the sliding keepers are let into the cylindrical segments of the cylinder a distance sufficient to bring their outer 80 faces substantially flush with the outer face of the segment and the walls of the cutaway portions of the segments in which the sliding keepers are seated serve to guide the said keepers in their sliding movements. 85 Each cylinder segment has fixed keepers at one edge and sliding keepers at its opposite edge.

To remove a chase, first loosen the set screws 24 which pass through the slots in 90 the sliding keepers, then slide the keepers back until the rear edge of the chase is unobstructed and then draw the chase rearward in its own plane off the bed of the form cylinder. To replace a chase, simply 95 reverse the above procedure.

The number of screws for holding the keepers in position is a matter of choice, and slight changes might be resorted to in the form and structure of the parts without 100 departing from the spirit and scope of my invention.

What I claim is:

1. The combination with a form cylinder

provided with a chase bed having undercuts at its opposite ends, of a type chase having its ends and front and rear edges beveled, a fixed keeper arranged to engage one edge of the chase and a curved sliding keeper arranged to conform to and engage the opposite beveled edge of the chase.

2. The combination with a form cylinder provided with a chase bed having undercuts at its opposite ends, of a type chase having its ends and front and rear edges beveled, a curved fixed keeper arranged to conform to and engage one beveled edge of the chase and a curved sliding keeper arranged to conform to and engage the opposite beveled edge of the chase.

3. The combination with a type chase provided with beveled edges and with recesses at the opposite ends of one beveled edge, of a form cylinder provided with a bed having undercuts at its opposite ends for receiving two of the opposite beveled edges of the

chase and with sliding keepers arranged to engage the chase in the said recesses.

4. In combination, a flat type chase provided with beveled edges and with recesses at one edge, a form cylinder provided with a flat chase bed and cylindrical segments at the opposite edges of the bed, the said bed having undercuts at its opposite ends to receive the ends of the chase, fixed keepers seated in one cylindrical segment and sliding keepers seated in the opposite cylindrical segment in position to enter the recesses at the edge of the chase. 25 30 35

In testimony, that I claim the foregoing as my invention, I have signed my name in presence of two witnesses, this 21st day of January 1910.

HENRY B. COOLEY.

Witnesses:
